UNITED STATES PATENT OFFICE.

CASWELL A. REAGAN, OF FELLOWS, CALIFORNIA.

EXPANDING WELL-DIGGING BIT.

1,095,419.

Specification of Letters Patent.

Patented May 5, 1914.

Application filed February 26, 1913. Serial No. 750,905.

To all whom it may concern:

Be it known that I, CASWELL A. REAGAN, a citizen of the United States, residing at Fellows, in the county of Kern and State of California, have invented a new and useful Expanding Well-Digging Bit, of which the following is a specification.

The device forming the subject matter of this application is a cutting structure adapted to be lowered into a well tubing, and to be assembled with the shoe at the lower end of the tubing, to the end that when the tubing and the shoe are rotated, the cutting structure will be rotated likewise.

15 The invention aims to provide novel means for directing the cutting structure into the place in the shoe, to provide novel means for locking the cutting structure to the shoe, for rotation therewith, to provide a cutting structure which will expand automatically beyond the contour of the shoe, so as to fashion an opening, in advance of the shoe, of greater diameter than the shoe.

Another object of the invention is to provide novel means whereby the cutting structure may be lowered into the well tubing and with equal facility be removed therefrom.

It is within the scope of the invention to improve generally, and to enhance the utility of, devices of that type to which the present invention appertains.

With the above and other objects in view which will appear as the description proceeds, the invention resides in the combination and arrangement of parts and in the details of construction hereinafter described and claimed, it being understood that changes in the precise embodiment of invention can be made within the scope of what 40 is claimed without departing from the spirit of the invention.

In the drawing:—Figure 1 shows the invention in vertical longitudinal section, parts being shown in elevation; Fig. 2 is a transverse section on the line 2—2 of Fig. 1; Fig. 3 is a transverse section on the line 3—3 of Fig. 1; Fig. 4 is a transverse section on the line 4—4 of Fig. 1; Fig. 5 is a transverse section on the line 5—5 of Fig. 1; Fig. 6 is a 45 transverse section on the line 6—6 of Fig. 1; Fig. 7 is a transverse section on the line 7—7 of Fig. 1; Fig. 8 is a transverse section on the line 8—8 of Fig. 1; and Fig. 9 is a fragmental longitudinal section, the bits 50 being advanced and drawn together.

In the drawing, the numeral 1 indicates a

section of the well tubing, to the lower end of which a shoe 2 of tubular form is attached, by threading or otherwise. In the interior of the shoe 2 are sinuous grooves 3, 60 at the lower end of which, transverse recesses 4 are formed, in the interior of the shoe 2, the lower edges of the recesses 4 defining shoulders 5. In the lower end of the shoe 2 there are oppositely disposed slots 55.

65 The invention further includes a cutting member which is adapted to be lowered into the shoe 2. The cutting member comprises a body 6 having at its upper end, a flange 7 provided with peripheral notches 8. The 70 primary bore of the body 6 is indicated by the numeral 10, and into the upper end of the bore 10 is threaded or otherwise secured a plug 11. Below the primary bore 10, the body 6 is equipped with transverse slots 12 75 communicating with the bore 10. In the outer face of the body 6 there is an annular recess 14. A slot 15 extends transversely through the body 6 and at its ends opens into the annular recess 14. Located below 80 the slot 15 and communicating therewith is a secondary bore 16, the upper end of which is closed by a plug 17 which may be threaded into place. The lower end of the secondary bore 16 is reduced in diameter as indicated at 18. Below the reduced portion 18 of the bore 16, the body 6 is provided with transversely disposed slots 19 having lateral extensions 20 which are prolonged through the outer face of the body 6, at the lower end 90 of the body. The upper ends of the slots 19 define shoulders 21 and the upper ends of the extensions 20 define shoulder 22. Rigidly held in place upon the body 6 and extended across the opening defined by the extensions 95 20 is a stop 23.

A main plunger 24 is provided, the same being equipped at its upper end with a head 25. The plunger 24 is mounted to slide in the plug 11 and is provided adjacent its lower end with a head 26, the lower end of which is rendered wedge-shaped as indicated at 27, the head 26 being mounted to slide in the primary bore 10 of the body 6. A compression spring 28 surrounds 105 the plunger 24 and abuts at one end against the plug 11, the other end of the spring 28 abutting against the upper face of the end 27 of the plunger. The wedge-shaped extension 27 of the head 26 is adapted to engage the beveled ends 29 of a pair of keys 110 30 which are mounted to slide in the trans-

verse slots 12. The keys 30 are equipped with slots 31, receiving pins 32, the pins 32 being terminally secured in the body 6. The pins 32 serve to limit the movement of the 5 keys 30, transversely of the head 6.

An auxiliary plunger 33 is located in the secondary bore 16 of the body 6 and is held for sliding movement in the reduced portions 18 of the bore 16. At its upper end, the 10 auxiliary plunger 33 is provided with a head 34 which is adapted to abut against the plug 17. A rod 35 extends through the head 34, the ends of the rod being mounted to slide in the transverse slot 15 which 15 communicates with the annular recess 14 of the body 6. The ends of the rod 35 are secured in an expansion ring 36 which may be of wedge-shape, the expansion ring being received within a resilient gasket 37 located in the recess 14. The expansion ring 36 and the resilient gasket 37 constitute what, for convenience may be denominated an "annular packing member." A compression spring 38 is located in the secondary 20 bore 16, one end of the compression spring 38 abutting against the head 34, the other end of the spring abutting against the lower portion of the head 6. A pin 39 extends transversely through the lower end 25 of the auxiliary plunger 33, the pin 39 being located in the slots 19. The upper ends of bits 40 are pivotally engaged upon the ends of the pin 39, for movement in a common plane with the pin, the bits being 30 overlapped upon each other, and being halved together as shown at 41. The upper 35 ends of the bits 40 are denoted by the numerals 42. The bits 40 are laterally extended to define shoulders 43. Below 40 the pin 39, the bits 41 are equipped with recesses 44 and below the recesses 44 are located shoulders 45 which project toward each other. The bits 40, below the shoulders 43 are provided with downwardly 45 diverging, inclined edges 46.

A fishing member is provided, the same comprising a head 47 to which a pipe or rod 48 may be secured by threading or otherwise. The head 47 is provided with a 50 bore 49 in which a main plunger 24 is slidably received, there being a transverse slot 50 in the head 47, communicating with the upper end of the bore 49. An arched spring 51 is located in the slot 50, the arm portions 55 of the spring 51 abutting against the head 47, at the upper end of the bore 49, the spring 51 being provided with inwardly projecting pawls 52. The spring 51 is held in place by a retaining member 53 which may be a removable block, the same 60 being interposed between the upper end of the spring 51 and the upper wall of the slot 50. Secured to the outer face of the head 47, below the slot 50, are a plurality 65 of convexed resilient arms 54, adapted to be

received in the notches 8 in the flange 7 of the member 6.

When it is desired to lower the cutting member into the tube, the retaining member 53 is withdrawn out of the slot 50 in the head 47, to set the spring 51 free, the spring 51 being removed. The lower ends of the arms 54 of the head 47 are engaged in the notches 8 and extend beneath the flange 7. The spring 28 abuts against the plug 11 and against the head 26 of the main plunger 24, pushing the main plunger downwardly, so that the wedge-shaped extension 27 of the head 26 will engage with the beveled ends 29 of the keys 30, forcing the keys 30 outwardly. The bits 40 are drawn downwardly, into the position shown in Fig. 9, the auxiliary plunger 33 riding in the portion 18 of the secondary bore 16. The bits 40 are then swung together as shown in Fig. 9, the fixed stop 23 being received in the recesses 44. The cutting structure is then lowered by means of the fishing tool into the tube 1, whereupon, the projecting ends of the keys 30 will ride into the sinuous grooves 3 and arrive ultimately in the recesses 4. The body member is then rotated, this operation being possible by reason of the fact that the lower ends of the arms 54 are engaged in the notches 8 in the flange 7. 90 When the body 6 is rotated in the manner hereinbefore described, the ends of the keys 30 will arrive in the ends of the recesses 4, and thus the body 6 will be held against upward movement.

When the keys 30 abut against the lower edges of the recesses 4, the bits 40 will be so positioned that they may expand, into the position shown in Fig. 1. When the shoe 2 no longer exerts a pressure against the edges of the bits 40, the spring 38 will force the auxiliary plunger 33 upwardly, the shoulders 45 sliding along opposite edges of the fixed stop 23, and thereby expanding the bits into the positions shown in Fig. 1. The shoulders 43 of the bits will come into abutment with the shoulders 22 of the body member 6, and the upper ends 42 of the bits will come into contact with the shoulders 21, the portions 43 of the bits being engaged in the slots 20, and the outer edges 46 of the bits being engaged in the grooves 55. Thus, the bits 40 will be disposed in expanded condition, as shown in Fig. 1, upward movement of the body 6 being prevented by the engagement between the ends of the keys 30 and the recesses 4. If the tubing 1 and the shoe 2 be rotated, rotatory movement will be imparted to the bits 40, and the bits 40 will cut, in advance of the shoe 2, a hole 115 which is of greater diameter than that of the shoe. So soon as the cutting mechanism has been placed, as hereinbefore described, the head 47 of the fishing tool is drawn upwardly by means of the rod or pipe 48, the 120 125 130

arms 54 springing outwardly and releasing their hold upon the flange 7 of the body 6.

To remove the cutting mechanism from the tubing 1, the spring 51 is mounted in the slot 50 and is held in place by the retaining member 53. If, now, the head 47 and attendant parts be lowered into the tubing 1, the pawls 52 of the spring 51 will engage with the head 23 of the main plunger 24, so that the plunger 24 and the head 6, together with the attached parts, may be drawn upwardly. When tension is applied to the main plunger 24, the spring 28 will be put under compression, and the head 26 will be lifted, so that the wedge-shaped extension 27 of the head no longer engages with the beveled ends 29 of the keys 30. The keys 30 will thus be set free, and the tool may be rotated, through the medium of the arms 54, so that the ends of the keys 30 may ride into the sinuous grooves 3.

When an upward pull is exerted on the head 6, in the manner hereinbefore described, the pressure of the loose material upon the edges 46 of the bits 40, will tend to hold the bits 40 down when the head moves upwardly, so that the fixed stop 23 may ride into the recesses 44, the spring 38 being put under tension, and the auxiliary plunger 33 sliding downwardly. Thereupon the bits 40 will move together as shown in Fig. 9, so as to traverse readily, the interior of the shoe 2 and the tube 1.

It is to be noted that when the bits 40 swing laterally into the positions shown in Fig. 1, the auxiliary plunger 33 moves upwardly, and when the plunger 33 moves upwardly, the rod 35 will be carried upwardly, the rod 35 carrying the expansion ring 36 upwardly, thereby compressing the gasket 37 outwardly against the inner face of the shoe 4. The foregoing operation takes place when the cutting mechanism is seated in the well. When, however, the cutting mechanism is removed from the well, the auxiliary plunger 33 moves downwardly, into the position shown in Fig. 9. When the auxiliary plunger 33 moves downwardly, the pin 35 and the expansion ring 36 are carried downwardly, and consequently, the pressure of the gasket 37 against the shoe 2 is released, the transverse slots 15 serving to permit the rod 35 to have the necessary sliding movement.

Having thus described the invention, what is claimed is:—

1. In a device of the class described, expandable bits; an annular packing member comprising a relatively fixed part and a movable part, one of which parts is beveled to expand the other, and means for connecting one of said parts with the bits to effect the expansion of the packing member when the bits are expanded.

2. In a device of the class described, a

body; an annular packing member extended transversely of the body and including a wedge shaped element upwardly movable on the body; a rigid structure connected with the annular packing member; bits pivoted to the said rigid structure; and a projection upon the body, engageable by the adjacent edges of the bits to hold the bits expanded.

3. In a device of the class described, a body; a packing member, a part of which is upwardly movable upon the body; a rigid structure connected with the said part; a bit pivoted to the rigid structure; a projection upon the body engaging the inner edge of the bit to hold the bit laterally extended; and resilient means for lifting the rigid structure.

4. In a device of the class described, a tubular member having a transverse recess; a cutting device including a body insertible into the tubular member and a bit upon the body projecting laterally beyond the lower end of the tubular member; a key slidable in the body and adapted to engage the recess; a plunger slidable in the body; the plunger and the key having mutually inclined parts adapted to advance the key into the recess when the plunger is depressed, and spring means for depressing the plunger.

5. In a device of the class described, a tubular member provided in its interior with a sinuous groove terminating in a transverse recess; a body slidable in the tubular member; a bit carried by the body; and yieldable locking means carried by the body, said means being adapted to ride into the groove and to travel thence into the recess.

6. In a device of the class described, a tubular member provided in its interior with a sinuous groove terminating in a transverse recess; a body slidable in the tubular member; a bit carried by the body; a key slidable in the body, the key being adapted to ride into the groove and to travel thence into the recess; and resilient means for forcing the key outwardly, to enter the groove.

7. In a device of the class described, a tubular member provided in its interior with a sinuous groove terminating in a transverse recess; a body slidable in the tubular member; a bit carried by the body; a key slidable in the body, a plunger slidable in the body, the plunger and the key having mutually inclined parts, adapted to advance the key into the groove, the key being adapted to move from the groove into the recess; and resilient means for actuating the plunger.

8. In a device of the class described, a tubular member provided in its interior with a sinuous groove terminating in a transverse recess; a body slidable in the tubular member; a bit carried by the body; a key slidable in the body, the key being adapted

- to ride into the groove and to travel thence into the recess; a plunger mounted to slide in the body, the plunger being provided with an enlarged head, the head and the 5 key having mutually inclined parts adapted to actuate the key when the plunger is actuated; a spring surrounding the plunger and abutting against the head; and a member carried by the head and constituting at 10 once, means for directing the sliding movement of the plunger and an abutment for the spring.
9. In a device of the class described, a tubular member having a recess; a body 15 movable in the tubular member; a bit carried by the body; a key slideable in the body and adapted to engage the recess; a plunger slideable in the body and constituting means for advancing the key into the recess when 20 the plunger is depressed; and a lifting member having means for engaging the plunger to lift the plunger and set the key free.
10. In a device of the class described, a tubular member having a recess; a body 25 slideable in the tubular member; a bit carried by the body; a key slideable in the body and adapted to engage the recess; a plunger slideable in the body and constituting means for advancing the key into the recess; a lifting 30 and lowering member; means upon the said member for detachably engaging the body; and removable means on the said member for securely engaging the plunger.
11. In a device of the class described, a tubular member having a recess; a body 35 slideable in the tubular member; a bit carried by the body; a key mounted in the body and adapted to engage the recess; a plunger mounted to slide in the body and constituting 40 means for actuating the key to engage the recess; a lifting and lowering member; spring arms upon the said member, detachably engaged with the body; and a spring actuated pawl upon the said member, adapted 45 to engage with the plunger.
12. In a device of the class described, a tubular member having in its interior a sinuous groove terminating in a transverse 50 recess; a body mounted to slide in the tubular member; a bit carried by the body; a member carried by the body and adapted to enter the groove and to ride, thence, into the recess, when the body is rotated; and a lowering device including resilient arms 55 detachably engaged with the body, the arms being engaged with the body to secure a rotation of the body.
13. In a device of the class described, a body; a bit carried by the body; a key projecting from the body; a lowering device including 60 spring arms, detachably engaged with the body, the body being notched to

receive the arms, whereby the body may be rotated when the lowering member is rotated.

65

14. In a device of the class described, a body; an expansible element upon the outside of the body; a member interposed between the expansible element and the body, to effect an expansion of the expansible element; a plunger slidably mounted in the body; a bit pivotally connected with the plunger; and a connection between the plunger and said member.

70

15. In a device of the class described, a body; a gasket surrounding the body; an expansion ring interposed between the gasket and the body; a plunger mounted to slide in the body; a connection between the plunger and the expansion ring; and a bit pivotally connected with the plunger.

75

16. In a device of the class described, a body; a gasket upon the outside of the body; an expansion member interposed between the gasket and the body; a plunger slidably in the body; a bit pivotally connected with the plunger; a connection between the plunger and the expansion member; and resilient means actuating the plunger to cause a lateral movement of the bit, and to cause an advancing of the expansion member into the gasket.

80

17. In a device of the class described, a body; a gasket upon the body; an expansion member movable between the gasket and the body; a bit mounted to swing beyond the periphery of the body; and means operatively connecting the expansion member and the bit for simultaneously swinging the bit beyond the periphery of the body and for advancing the expansion member into the gasket.

85

18. In a device of the class described, a body; a gasket surrounding the body; expansible bits; and automatically operating means for simultaneously expanding the bits and expanding the gasket.

90

19. In a device of the class described, a body; a bit carried by the body; key moving means carried by the body; a combined lifting and lowering member; means upon the lifting and lowering member for detachably engaging the body; and removable means upon the lifting and lowering member for securely engaging the key moving means.

95

In testimony that I claim the foregoing as my own, I have hereto affixed my signature in the presence of two witnesses.

CASWELL A. REAGAN.
